UNITED STATES PATENT OFFICE.

GUILLAUME DE CHALMOT, OF LEAKSVILLE, NORTH CAROLINA, ASSIGNOR
TO THE WILLSON LABORATORY COMPANY, OF NEW YORK, N. Y., A
CORPORATION OF WEST VIRGINIA.

PRODUCTION OF NITROGEN COMPOUNDS.

SPECIFICATION forming part of Letters Patent No. 741,396, dated October 13, 1903.

Application filed January 23, 1896. Serial No. 576,521. (No specimens.)

To all whom it may concern:

Be it known that I, GUILLAUME DE CHALMOT, a subject of the Queen of the Netherlands, (having declared my intention of becoming a citizen of the United States,) residing at Leaksburg, in the county of Rockingham and State of North Carolina, have invented certain new and useful Improvements in the Production of Nitrogen Compounds, 10 of which the following is a specification.

This invention relates to the production of nitrides of metals or metalloids in the electric furnace and the production of ammonia from such nitrides.

15 If oxids or salts of metals or metalloids are mixed with carbonaceous matter and heated in the electric furnace while a current of nitrogen is passed through the material, the metals or metalloids take up a considerable 20 amount of nitrogen, which is bound in the form of nitrides almost wholly, with occasional traces of cyanides. There can thus be obtained nitrides of calcium, (Ca_3N_2), of barium, (Ba_3N_2), of aluminium, (AlN), and of 25 titanium, (TiN_2). In such tests I have found the nitrides mixed with carbids, oxids, and graphite or other form of carbon. Definite formulae for the reactions which take place cannot therefore be given. I have found that in 30 these reactions it is not sufficient to pass the nitrogen over the mass in the furnace; but it is practically essential that it shall be forced through the mass. In the case of fused material it becomes exceedingly difficult in 35 the electric furnace to effect a passage of the nitrogen through the mass so as to bring about an extensive contact between it and the molten material because of the extreme fluidity of the material at the excessively high 40 temperature attained. One purpose of my invention is to overcome this difficulty. To this end I conduct the reaction with an excess of carbon, whereby the material is rendered very porous, and thus the nitrogen can 45 be forced through the entire porous mass and brought into intimate contact with all the reduced metal. In fact, such a perfection of porosity is thus attained as to render it feasible to introduce nitrogen on top of the mass

in the furnace and cause it to circulate downward through the mass. In order to obtain ammonia from these nitrogen compounds, they are treated with steam at red heat. The steam should first be superheated; but if not it will become so by contact with the hot 55 compounds. In the case of barium, calcium, and other basic elements the ammonia is easily obtained in this manner from their nitrides or cyanides. In the case of titanium it is preferable to mix its nitrid with a basic 60 oxid and then subject the mixture to superheated steam.

The treatment of the nitrides with steam for recovering the ammonia might be effected at any time by heating the nitrid and then passing the superheated steam over or through it. It is, however, practically of great advantage to carry out this treatment while the nitrogen compound is still exposed to the heat of the electric furnace.

70 My invention therefore provides not only that the nitrogen shall be forced through the porous highly-heated mass in the furnace, but also that superheated steam shall at the same time be forced through the mass in order that the nitrogen which is fixed as a nitrid shall almost immediately afterward be converted into ammonia. This operation is greatly facilitated by the porosity of the mass in the furnace, which renders it feasible to 75 institute a downward circulation of the gases through the mass.

My invention further provides for a substantially continuous treatment in the furnace by feeding it continually with fresh material from 80 above and causing the material under action to slowly descend at a rate to insure that the greater part of the material shall be acted upon and reduced by the electrically-generated heat in the furnace, the nitrogen being 85 introduced at the top of the furnace and circulated downward past the electrodes, and the superheated steam being introduced preferably beneath the electrodes, the combined gases being thus circulated downward 90 through the porous mass and drawn off at any convenient point beneath, while the entire mass is caused to gradually descend and

is finally removed at the bottom of the furnace. I have devised an apparatus for carrying out this process.

It is well known that titanium takes up nitrogen more readily than any other known element. I therefore prefer to employ titanium oxid (rutile, brookite, or anatase) or a high-grade titaniferous ore. With these materials I prefer to proceed as follows: The titaniferous material is pulverized and mixed with a basic oxid, preferably caustic lime, and also mixed with carbonaceous material, preferably coke or charcoal. The mixture is subjected to the heat of an electric arc, and nitrogen is forced through the semimolten material. While still quite hot, steam is forced into the mixture. The carbids and nitrides which were first formed are thus decomposed, and the original oxides—that is, titanium oxid and caustic lime—are again obtained. The nitrogen forms ammonia and the carbon forms carbon monoxide, while hydrogen is at the same time liberated from the decomposition of the steam. The lime and titanium oxid can then be mixed anew with carbon and used a second time. As some titanic acid is liable to be carried over with the gases which pass out of the furnace and as this acid is somewhat expensive the gases are conducted through settling-rooms and flues and washing apparatus, where all the titanium oxid dust can settle. Some of the dust thus recovered is titanium nitrid, which is volatilized in the arc.

Instead of titanium oxid other oxides may be used. Alumina has given me especially favorable results. Instead of lime other bases, like soda or potash, would be equally effective; but these are subject to the objections of being too expensive, too volatile, and of acting on the bricks of the furnace.

I will now describe the apparatus which I have devised for carrying out my new process and which I believe is the best adapted to that end.

Figure 1 of the accompanying drawings is a vertical mid-section through the electric furnace. Fig. 2 is a horizontal section thereof on the line 2 2 in Fig. 1. Fig. 3 is a vertical section on the line 3 3 in Fig. 2, showing the dust-separator and ammonia-absorber. Figs. 4 and 5 are fragmentary sections showing two modified constructions for the lower part of the furnace shown in Fig. 1. Fig. 6 is a sectional elevation showing a modified construction.

Referring to Fig. 1, let A indicate an upright shaft, stack, or chimney, which may be made of masonry. In the upper part of this stack is formed a chamber B, constituting the chamber of the electric furnace. Into this chamber project electrodes C C, consisting of bars, slabs, or pencils of carbon and which are constructed to be relatively movable through openings in opposite sides of the furnace-wall in order to vary the length of the arc or the quantity of material interposed be-

tween the pencils and acted upon by the electric current passing between them. Both may be movable or one fixed and the other movable. Above the chamber B is mounted a hopper D, having a controlling slide or feed-door E at its bottom. This hopper is designed to contain the pulverized and mixed material to be fed to the furnace. Beneath the electrodes C C the furnace-chamber B is preferably contracted or formed with a hopper-bottom, as shown at B', and from this portion the chamber extends downward, preferably, as an upright chamber of uniform cross-section. This chamber is designated F. In this chamber F, I have shown in Fig. 1 a piston G, mounted to work freely up or down in the chamber and supported on a rod g, which is engaged between rollers g' g², one of which is preferably formed with cog-teeth to engage corresponding rack-teeth on one side of the rod g, so that by turning the wheels g' g² the piston may be raised or lowered. A pit g³ is provided for receiving the rod g when the piston is lowered. The lowermost position of the piston is indicated in dotted lines at G'. Just above this position the stack is formed with an opening H, closed by a suitable door.

A nitrogen-pipe I enters the upper part of the furnace-chamber B for introducing nitrogen thereinto. In practice I prefer to employ atmospheric nitrogen in the form of what is known as "producer-gas" or "generator-gas" consisting of a mixture chiefly of nitrogen and carbon monoxide. I have shown in Fig. 1 a gas-producer J of ordinary construction and a blower K for forcing air through it, the producer being fed with coal which is brought to incandescence and the air then forced through it in the well-known manner. The producer-gas thus generated is introduced into the chamber B and caused to flow down through the mass of material. At any suitable point or points in the lower part of the chamber B or upper part of the chamber F openings or twyvers a a are provided for introducing superheated steam. Steam is fed to these openings through pipes S S, Fig. 2, which communicate with passages a' in the masonry, from which passages the twyvers a a branch.

For permitting the escape of the gases from the chamber the furnace is formed on one or both sides with a perforated plate or partition b, from which leads an opening or space c in the masonry, and from this extends a pipe d, which leads to the dust-separator L, Fig. 2. I have shown the outlets b c d as arranged on two opposite sides of the furnace. The plates b b may be made of porcelain or of metal, (iron.) In the former case they may and in the latter case they must be cooled by the circulation of cold water through them. In Fig. 2 I have shown the left-hand plate b as made hollow for this purpose. The right-hand plate (shown in plan) is supposed to be similarly constructed. Both plates are connected at one side with an inlet water-pipe W and

at the other side with an outlet water-pipe W'. The water-current should be rapid by circulating the water under high pressure.

The dust-separator may be variously constructed. The construction shown in Fig. 3 consists of a casing L, into which the gases enter by pipes d d at the top on opposite sides, are thence deflected downward by partitions e e, and flow thence upward to the inlet of a pipe f, which carries the gases down out of the separator and delivers them to the gas-washer and ammonia-absorber.

For washing the gas it is caused to pass from the pipe f into a chamber g, which is sealed in water, so that the gas has to pass beneath the water seal and bubble up through the water on the opposite side of a partition which separates this chamber from the chamber h. By this means any particles of dust which have not been caused to settle to the bottom of the dust-separator L are washed out or arrested and retained in the water seal beneath the chambers g h.

For separating the ammonia from the gas any suitable kind of ammonia-absorber may be employed—such, for example, as any construction commonly used in gas-works for separating ammonia from illuminating-gas. I have shown at M one construction of ammonia-absorber that may be employed. It consists of an upright casing in which is arranged an alternating series of inclined shelves i i, extending each from one side across part way toward the other. In the construction shown the chamber h, already referred to, constitutes the bottom chamber of this absorber. Cold water is introduced by a pipe j and falls on the upper shelf i, flowing across this shelf and falling onto the next, flowing over this and falling onto the next below, and so on, the water thus having a zigzag course down the casing and finally falling into the water seal at the bottom in the chamber h. The gas which bubbles up into the chamber h is caused to circulate in an upward zigzag path, so that it flows over the streams of water on the shelves i i and flows through the successive waterfalls at the lower edges of these shelves, so that the gas continuously comes in contact with fresher and cooler water, by which the ammonia contained in the gas is absorbed, and the gas finally passes out by a pipe k and is drawn off by a suction-blower N. The water which is falling from plate to plate has taken up the ammonia from the gas flows out as ammoniacal liquor through a pipe l. Another mode of recovering the ammonia is to absorb it by an acid, as sulfuric acid.

In operation the piston G is first raised to its highest position close beneath the perforated plates b. The titanic oxide or other metallic oxid, the lime or other base, and the carbon having been pulverized and mixed together are placed in the hopper D. Sufficient material is caused to fall from this hopper into the chamber B to fill the furnace up to

and around the electrodes C C. The furnace operation can then begin. The electrodes C C being connected at the opposite terminals 7c of an electric circuit fed by a suitable generator or transformer, (either continuous or alternating currents being suitable,) the electric current is caused to pass from one electrode to the other through the intervening 75 mass of material, whereby the latter is heated to white heat, the operation being controlled by drawing the electrodes apart or feeding them together, as may be necessary. At the same time producer-gas is introduced at I 80 under a pressure just sufficient to prevent any air being sucked into the furnace—that is to say, its pressure is slightly more than that of the atmosphere. The suction-blower N is set in operation, being driven at such speed as 85 to generate just sufficient suction to draw the gas through the mass of pulverulent material in the furnace and through the dust-separator L and ammonia-absorber M. Consequently the gas introduced at I under sub- 90 stantially atmospheric pressure is drawn down through the porous mass by suction. The action of the electrically-generated heat in the furnace is to reduce the metallic oxid and the basic oxid, the incandescent reduced 95 materials being exposed to the nitrogen of the producer-gas, and thereby converted partly into nitrides and partly into carbids. As fast as this reduction occurs the piston G should be lowered by turning the wheels g' 100 and g², and fresh material should be introduced from the hopper D by opening the slide E. Any other means for feeding the material may be substituted for this slide. In this way a sufficient mass of unreduced material 105 is kept piled above the electrodes, while the nitrides and carbids are continually caused to descend to positions opposite the twy whole and outlet-openings b b. As soon as the nitrides, &c., have come to the level of the twy whole super- 110 heated steam should be turned on through the pipes S S and injected through these twy whole into the material. This steam decomposes the nitrides, generating ammonia and hydrogen, which, with the residue of the producer-gas, is drawn off through the perforations b and passed through the dust-separator, where any particles of dust or ashes, including particles of titanic acid, are caused 115 to settle. The gases then pass down through the pipe f to the water-chamber g, where they are forced through water to take out any further particles of dust. The gases then pass upward through the ammonia-absorber, where the ammonia is taken up by the water. The 120 remaining gas then passes out through the pipe k and blower N and being a combustible gas substantially devoid of nitrogen it may be conducted to gas-burners or any apparatus in which such gas can be utilized. 125 The furnace operation continues as described until the piston G has descended to its lowest position G', whereupon the furnace operation is stopped, and as soon as the mass is suffi-

ciently cooled the door H is opened and the material is drawn out through this door. This material consists of substantially the original mixture of metallic oxid and lime and may be used again by grinding it and mixing it again with carbon. In the case of an impure carbon, such as coke, the mixture which is taken out contains also the ash therefrom, in which case the material may be used over and over again until the proportion of ash becomes so much as to render it unprofitable to continue to reemploy the material.

By using an excess of carbon beyond that which is required chemically to effect the reduction of the metallic oxid the reduced material in the furnace is made very porous. This is especially important in the use of titanium, since its nitrid has all the properties of a metal and has a very high fusing-point, so that it is very desirable to keep its particles apart. The porosity is further promoted by the mixture of titanium oxid with lime, which after reduction forms a mixture of titanic nitrid, calcium carbid, and calcium nitrid. The steam on coming in contact with the calcium carbid and nitrid decomposes these compounds at once, forming calcium oxide and gases like carbon monoxid, carbon dioxide, hydrogen, ammonia, &c. The driving off of these gases makes the material still more porous, since the calcium oxide which is thus reconstituted is not hot enough to run together. The resulting porosity of the material allows the steam to come also into contact with the titanic nitrid, which would not occur if this latter were alone present, since in that case the water-vapor would act only on the surface of this nitrid, forming titanic acid, which would withstand the further action of the vapor. It is also probable that the presence of the base (lime) furthers the decomposition of the titanic nitrid by uniting with a part of the resulting titanic acid. The reaction between superheated steam and titanium nitrid is

The effect of adding a base, as soda or lime, is that it unites with the titanic oxid that is set free by the steam and forms a salt called a "titanate," (titanic oxid having acid properties,) the reaction being as follows, with soda:

The presence of a base facilitates the reaction between the superheated steam and the titanic nitrid, one of the reasons therefore being that the titanates fuse at a lower temperature than the titanic oxid, so that the base acts thus as a flux.

The furnace may be modified in the manner shown in Fig. 4 by constituting a screw conveyer P for the piston G, this conveyer acting to continuously or intermittently dig out the material from the bottom of the chamber F, so that the process may be made, in

effect, continuous, or such a construction as is suggested in Fig. 5 may be employed, where the mass settles down to the bottom of the chamber F and can be shoveled out through a door Q, its descent being facilitated by poking through a poke-opening Q'.

Fig. 6 shows a modified construction of furnace wherein a tubular carbon pencil C' is used as one electrode and an iron plate C², forming the bottom of the furnace-chamber and covered with a layer of carbon, constitutes the other electrode, these being connected in circuit with a dynamo or other generator D' in the ordinary manner. Nitrogen or producer-gas is introduced through a pipe I' and superheated steam through a pipe S', either of these in alternation or both together being conducted under control of valves 10 and 11 through a flexible pipe R to the hollow in the carbon pencil C', the gases flowing down through this carbon pencil to the bottom thereof and then ascending through the mass of material in the furnace and passing out through a pipe d', which leads to any suitable dust-separator and ammonia-absorber. This apparatus may be operated by first circulating nitrogen through the furnace during the maintenance of the arc and then discontinuing the arc and circulating superheated steam through the highly-heated mass in the furnace and repeating the operations alternately.

My invention may be carried into effect by means of other constructions of electric furnace than those hereinbefore described and shown, and I do not limit myself to any particular construction of furnace for practicing the novel process which I have invented.

My invention is not limited to the employment of electrically-generated heat solely for carrying out the process. It is within my invention to effect the preliminary heating of the materials by heat otherwise generated—as, for example, in any ordinary furnace heated by combustion—thus raising the materials to as high a temperature as is practicable by such means and then subjecting them to the action of an electric arc to further raise the temperature to that necessary to accomplish the conversion of the oxid or salt into a nitrid, cyanid, or carbid.

This process has the advantage of saving a part of the electrically-generated heat, which is expensive, and substituting for it heat generated from fuel.

I claim as my invention the following defined novel features, substantially as hereinbefore specified, namely:

1. The process which consists in heating the oxid or salt of a metal or metalloid with an excess of carbonaceous matter in an electric furnace, so as to reduce the metal or metalloid while forming a porous permeable mass, and passing nitrogen through the heated porous mass at so high a temperature as to form a nitrid rather than a cyanid of the metal or metalloid.

2. The process which consists in heating the oxid or salt of a metal or metalloid with an excess of carbonaceous matter in an electric furnace, so as to reduce the metal while forming a porous permeable mass, simultaneously passing nitrogen through the heated porous mass while maintaining so high a temperature as to form a nitrid rather than a cyanid of the metal or metalloid, and subsequently passing superheated steam through the porous mass to decompose the nitrid and form ammonia. 55
3. The process which consists in heating the oxid or salt of a metal or metalloid with carbonaceous matter in an electric furnace so as to reduce the metal or metalloid, passing nitrogen through the heated mass while maintaining so high a temperature as to form a nitrid rather than a cyanid of the metal or metalloid, and while the mass is still highly heated passing superheated steam through it to decompose the nitrid and form ammonia. 60
4. The process which consists in heating the oxid or salt of a metal or metalloid with an added base and with carbonaceous matter in an electric furnace, so as to reduce the metal or metalloid and convert the base into a carbide, simultaneously passing nitrogen through the material while maintaining so high a temperature as to form a nitrid rather than a cyanid, and subsequently exposing the material to superheated steam to decompose the nitrid and form ammonia. 65
5. The process which consists in heating a titaniferous compound with an added base and carbonaceous matter in an electric furnace, so as to reduce the titanium, and passing nitrogen through the heated material in the furnace while maintaining so high a temperature as to form nitrids rather than cyanids, thereby forming a mixture of titanic and basic nitrids. 70
6. The process which consists in heating a titaniferous compound with a base and carbonaceous matter in an electric furnace, so as to reduce the titanium, passing nitrogen through the material in the furnace while maintaining so high a temperature as to form a mixture of titanic and basic nitrids (rather than cyanids) or carbids, and subsequently exposing these to superheated steam to decompose the nitrids and form ammonia. 75
7. The process which consists in heating a titaniferous compound with lime and carbonaceous matter in an electric furnace, passing nitrogen through the material in the furnace under so high a temperature as to form nitrids, whereby is formed a mixture of titanic and calcic nitrids and calcium carbide, and subsequently exposing these to superheated steam to decompose the nitrids and form ammonia. 80
8. The process which consists in exposing a mixture of the oxid or salt of a metal or metalloid with carbonaceous matter to the heat generated by the passage of an electric current between electrodes, whereby the metal is reduced, causing the mass to descend in proportion as the reduction takes effect to bring fresh material within the action of the current, and to lower the reduced material beyond the electrodes, and passing a current of nitrogen downwardly through the mass, whereby it is brought into contact with the metal or metalloid, at the instant of its reduction while maintaining so high a temperature as to form a nitrid rather than a cyanid of the metal. 85
9. The process which consists in exposing a mixture of the oxid or salt of a metal or metalloid with carbonaceous matter to the heat generated by the passage of an electric current between electrodes, whereby the metal or metalloid is reduced, causing the mass to descend in proportion as the reduction takes effect to bring fresh material within the action of the current, and to lower the reduced material beyond the electrodes, passing a current of nitrogen downwardly through the mass, whereby it is brought into contact with the metal or metalloid at the instant of its reduction while maintaining so high a temperature as to form a nitrid rather than a cyanid of the metal or metalloid, and simultaneously introducing superheated steam into the mass in contact with the newly-formed nitrid to decompose the same and form ammonia. 90

In witness whereof I have hereunto signed my name in the presence of two subscribing witnesses.
